(57) **CLAIM**

The ornamental design for an ice shaving blade, as shown and described.

DESCRIPTION

FIG. 1 is a bottom plan view of an ice shaving blade.

FIG. 2 is an end view thereof.

FIG. 3 is a top plan view thereof.

FIG. 4 is an opposite end view thereof.

FIG. 5 is a right side view thereof.

FIG. 6 is a top, right side perspective view thereof; and,

FIG. 7 is a bottom, left side perspective view thereof.
The ice shaving blade is depicted broken in the center to illustrate that it is of no specific length.
